UNITED STATES PATENT OFFICE.

WILSON A. OLDS, OF MEDICAL LAKE, WASHINGTON.

ELECTRICAL-TREATMENT APPARATUS.

1,207,614.

Specification of Letters Patent.

Patented Dec. 5, 1916.

Application filed August 17, 1914. Serial No. 857,219.

To all whom it may concern:

Be it known that I, WILSON A. OLDS, a citizen of the United States, residing at Medical Lake, in the county of Spokane and 5 State of Washington, have invented certain new and useful Improvements in Electrical-Treatment Apparatus, of which the following is a specification.

An object of my invention is to provide 10 an apparatus in the form of a harness to be fitted to the body of a person and to be connected with one of the terminals of an electric circuit, the opposite terminal of which is adapted to be received in the mouth of 15 the person receiving the treatment and to thus cause a passage of the current through the body and to include the body as a part of the circuit.

A further object is to so construct the 20 harness that the energized portions thereof pass across the nerve centers and the trunk nerves.

With other objects in view, which will be hereinafter referred to, my invention consists in the peculiar combination and novel 25 arrangement of parts, such as will be more fully described in connection with the accompanying drawings and more particularly pointed out in the appended claim.

30 In the drawing, Figure 1 is a view in elevation showing the parts fitted to the body of a person and with the electrical connection formed thereto. Fig. 2 is a view in rear elevation of the body harness of the 35 device. Fig. 3 is a vertical sectional view on the line 3—3 of Fig. 2. Fig. 4 is a perspective view of the contact plates connected with one of the terminals of the energizing circuit.

40 The body harness comprises a plurality of thin strap bands of virgin copper (copper which has not been smelted) which bands are arranged to pass over the nerve centers and the trunk nerves and are each connected 45 at a common point and to a common source of electrical energy.

The band 1, which is of copper, is fitted up around the neck of the wearer to pass 50 across the back of the neck and across the nerve centers at the base of the skull, this band 1 is brought down over the chest of the wearer and is connected at its end to the zinc plate 2 which plate is made of a considerable size and is adapted to fit against 55 the abdomen of the person adjacent the stomach and to embrace beneath its area the

important nerves which control the functioning of the digestive organs. A belt 3 is connected at its end with the zinc plate 2 and this belt which is a thin copper band is 60 adapted to pass up and over the small of the back and to thus complete the contact entirely around that portion of the body within which the stomach and digestive organs are located. A copper band 4 is connected with the lower edge of the plate 2 and the greater portion of its length is 65 passed between the legs of the wearer and then divided so that its ends 5 and 6 may be brought up around the thighs of the 70 wearer and again connected with the plate 2. A shield or pad 7 is provided to be fitted beneath the straps 4 to prevent chafing of the body and if desired this pad may be made of a conductive material to perform 75 the same function as the band 4 and to, as it embraces and extends over a considerable portion of the lower part of the torso of the wearer, energizes the nerve centers in the lower portions of the body. 80

A contact plate 8 is secured to the band 1 preferably at the point where it crosses the nerve center at the base of the skull and a conductor 9 is provided to connect this contact plate with the positive terminal of 85 the battery 10 or with any other suitable source of mild electrical supply.

A conductor 11 is connected with the negative terminal of the battery and at the free end of the conductor the contact member 12 is connected, this contact member being of such form that it may be held in the mouth of the person receiving the treatment. 90

In using the apparatus, the harness will be fitted to the body as illustrated in Fig. 1, 95 then with the parts connected with the battery, the contact member 12 is held in the mouth of the person against the tongue. The path of travel of the current through the apparatus is then from the battery 10 100 through the conductor 9 to the plate 8 and thence through the band 1 to the zinc plate 2 and to each of the straps connected therewith, then as the contact plate 12 is held in the mouth of the person and this contact 105 is connected with the negative terminal of the battery by the conductor 11, the circuit will pass through the body of the person and back to the contact plate 12 from whence it will pass through the conductor 11 and back 110 to the battery, thus causing a completion of the circuit wherein the body is included to

bridge the gap between the negative and positive electro-energized elements of the apparatus.

While the connection of the apparatus has hereinbefore been described as a direct contact of the parts with the body of the person, this apparatus can be used by adjusting the harness to the body of the person, placing the contact plate 12 in a glass or other 10 receptacle containing a mineral water which has chemical properties and mineral ingredients to cause electrical conductivity and then by taking the water from the receptacle through a straw, a glass tube, or 15 other non-conducting tube, the circuit connection will be completed through the liquid and the passage of the stream to the stomach will cause a direct transmission of the electric current at all points which may be contacted by the flow of liquid. No particular 20 property essential to the mineral water used in this connection will be herein taken up but it will be understood that any mineral water may be used so long as the properties 25 thereof are of such a nature as to render it capable of conducting an electric current.

From the foregoing it will be seen that I have provided an electrical treatment apparatus which is simple in construction and 30 in use, and which is so arranged that an electrical stimulating effect is transmitted through the body structure direct to the nerve centers and the trunk nerves by which the members of the body are connected, and 35 further it will be seen that the direct passage of current through the bodily structure

rather than an external application or a vibratory movement accomplished by electrical energy, is affected to destroy disease germs and to build up weak and devitalized 40 parts of the body structure.

While I have herein shown and described one specific form of my invention, it will be understood that slight changes might be made in the form and arrangement of the 45 several parts without departing from the spirit and scope of my invention, and hence I do not wish to be limited thereto except for such limitations as the claim may impose. 50

I claim:—

An electric treatment device for application to the human body including a zinc plate and means for supporting such plate adjacent the abdomen of the patient, such 55 means comprising a conducting band attached at each end to the top of said zinc plate and looped around the neck, a conducting band attached to the bottom of said plate and passed backwardly between the 60 legs divided into two parts passing upwardly over the thighs in opposite directions and brought in toward each other and attached to the sides of said zinc plate to hold the latter in a fixed location against 65 the abdomen.

In testimony whereof I affix my signature in presence of two witnesses.

WILSON A. OLDS.
